(57) **CLAIM**

The ornamental design for a handle for cookware as shown and described.

DESCRIPTION

FIG. 1 is a top, front and right side isometric view of a handle for cookware showing our new design;

FIG. 2 is a bottom, front and left side isometric view thereof;

FIG. 3 is a top plan view thereof;

FIG. 4 is a bottom plan view thereof;

FIG. 5 is a right side elevation view, the left side elevation being a mirror image thereof;

FIG. 6 is a front elevation view thereof;

FIG. 7 is a rear elevation view thereof;

FIG. 8 is a cross-sectional view taken along line 8-8 of FIG. 3;

FIG. 9 is a top, front and right side isometric view of a handle for cookware showing our new design;

FIG. 10 is a bottom, front and left side isometric view thereof;

FIG. 11 is a top plan view thereof;

FIG. 12 is a bottom plan view thereof;

FIG. 13 is a right side elevation view, the left side elevation being a mirror image thereof;

FIG. 14 is a front elevation view thereof;

FIG. 15 is a rear elevation view thereof; and,

FIG. 16 is a cross-sectional view taken along line 16-16 of FIG. 11.

The broken lines shown in the drawings are included for the purpose of illustrating environmental structure and form no part of the claimed design.

1 Claim, 10 Drawing Sheets
